United States Patent

Des. 242,548

Patented Nov. 30, 1976

242,548

TREE STEP

Charles L. Zane, 442 Ackerman Drive,
Chesterton, Ind. 46304

Filed Sept. 19, 1975, Ser. No. 614,914

Term of patent 14 years

Int. Cl. D25—02

U.S. Cl. D25—69

Fig. 1

Fig. 7

Fig. 2

Fig. 5

Fig. 3

Fig. 6

Fig. 4

FIG. 1 is a perspective view of a tree step showing my new design;

FIG. 2 is a top plan view thereof;

FIG. 3 is a side elevational view thereof;

FIG. 4 is a bottom plan view thereof;

FIG. 5 is a back elevational view thereof;

FIG. 6 is a front elevational view thereof; and

FIG. 7 is a side elevational view thereof opposite to the view of FIG. 3.

I claim:

The ornamental design for a tree step, substantially as shown.
